UNITED STATES PATENT OFFICE.

WILLIAM GREASON, OF DETROIT, MICHIGAN.

OIL CUP.

Application filed November 1, 1926. Serial No. 145,479.

My invention relates to a new and useful improvement in an oil cup such as commonly used by artists, in which is deposited the artist's oil. The artist in his work, and particularly in landscape work, is required to carry his materials afield, and in the execution of his work, it is highly desirable that the oil cup be readily accessible for use in the field. It is also desirable that this oil cup be mounted on the pallet and so arranged that the pallet may be carried in a vertical position without disturbing the oil cup and without spilling the oil therefrom.

To accomplish this I have provided an oil cup of novel structure, the object being the provision of an oil cup which may be carried in tilted or inverted position without spilling the oil therefrom.

Another object of the invention is the provision of an oil cup of this class which will be simple of structure, economical of manufacture and highly efficient in use.

Another object of the invention is the provision in an oil cup of this class of a cover therefor having an inwardly projecting safety sleeve so arranged and constructed on the cover and relatively to the cup itself as to prevent passage of oil therefrom upon a tilting of the cup.

Other objects will appear hereinafter.

The invention consists in the combination and arrangements of parts hereinafter described and claimed.

The invention will be best understood by a reference to the accompanying drawings which form a part of this specification and in which,

Fig. 1 is a perspective view of the invention with a part cut away.

Fig. 2 is a central vertical sectional view of the invention.

Fig. 3 is a side elevational view of the invention showing the cover in raised position and with a part of the cup broken away.

As shown in the drawings the invention comprises a cup 7 having a central portion 8 of its base offset to provide below the base proper of the cup an auxiliary reservoir 9 which is in communication with the interior of the cup proper. Mounted upon the outer surface of the central portion 8 by soldering, welding, or in any other suitable manner, is one end 10 of a resilient strip of metal, the other end 11 of which is doubled over to provide a spring clip between which

the pallet 12 may be inserted, the clip thus formed serving to retain the cup 7 firmly on the pallet so that the user may carry the pallet certain that the cup will not be detached therefrom under ordinary circumstances. The cover 13 is provided for the cup, this cover being cup shaped and having a side wall 14 for embracing the cup 7. The central portion of the cover 13 is pressed inwardly to provide a sleeve 15 which extends well downwardly toward the auxiliary reservoir 9. The size of the cylindrical portion 15 of the cover 13 is proportioned to the size of the cup 7 so that when the cup 7 is laid on its side, the cubical area between the lower side of the cup and the lower side of the sleeve 15 will be sufficient to contain the oil ordinarily placed in the cup 7, the depressed portion of the bottom of the cup serving, on account of the provision of the auxiliary reservoir 9, to provide this area so that by a tilting or an upsetting of the cup no spilling of oil from the cup will take place.

By providing the reservoir 9 formed as described a deep amount of oil is provided accessible to the user directly opposite the entry openings, while at the same time, the amount of oil contained in the cup 7 is reduced to a minimum.

An oil cup constructed in this manner has proven quite efficient in use, and has definitely overcome the difficulties and provided the advantages enumerated herein.

While I have illustrated and described the preferred form of my invention, I do not wish to limit myself to the precise form of structure shown, but desire to avail myself of such variations and modifications as may come within the scope of the appended claims.

Having thus described my invention what I claim as new and desire to secure by Letters Patent is:

1. An oil cup of the class described comprising a cup having the central portion of its base outwardly offset to provide a reduced receptacle in communication with the main body of said cup; a cover for said cup, said cover having an entry opening formed therein; and a tubular member projecting inwardly from said cover around said entry opening.

2. An oil cup of the class described comprising a cup having the central portion of its base outwardly offset to provide a re-

duced receptacle in communication with the main body of said cup; a cover for said cup having an entry opening formed centrally therein; a tubular member projecting inwardly of said cup from said cover around said entry opening, said tubular member projecting inwardly of said cup into close proximity to the level of the main body of said cup.

10 3. An oil cup of the class described comprising a cup having a central portion of its base outwardly offset to provide a reduced receptacle in communication with the main body of said cup; a cover for said cup having an entry opening formed therein

centrally thereof; and a cylindrical tubular member projecting inwardly from said cover around said opening.

4. An oil cup of the class described comprising a cup having the central portion of its base outwardly offset to provide a receiving portion of reduced diameter in communication with the main body of said cup; a spring clip mounted on said base and adapted for embracing a supporting surface 25 for attaching said cup thereon.

In testimony whereof I have signed the foregoing.

WILLIAM GREASON.
